P. J. SIMMEN

TRAIN CONTROL SYSTEM

Filed April 15, 1922

PAUL T. SIMMEN

PAUL J. SIMMEN

by John Powers.

Attorney

UNITED STATES PATENT OFFICE.

PAUL J. SIMMEN, OF EDEN, NEW YORK.

TRAIN-CONTROL SYSTEM.

Application filed April 15, 1922. Serial No. 553,204.

To all whom it may concern:

Be it known that I, PAUL J. SIMMEN, a citizen of the United States, residing at Eden, in the county of Erie and State of New York, have invented certain new and useful Improvements in Train-Control Systems, of which the following is a specification.

This invention relates to train control systems of the broad or general type wherein train movements are regulated by central office apparatus under the control of a despatcher and train movement regulating devices (such, for example, as signals) carried by the vehicle are severally responsive in operation to particular electrical conditions of short third rails or ramps placed at the entrance of stations or block divisions of the line. The deenergized condition of the third rails is one of the electrical conditions thereof to which the train movement regulating means is responsive and is utilized to produce an operation of said means which will conform to danger conditions, for example, the display of a danger signal.

The principal object of the invention is to give the despatcher fuller and more certain information concerning train movements and greater facility in the control of such movements and the utilization of track capacity.

A further object of the invention is to provide a record by which the de-energized condition of the third rail and the movement of the train in relation to such de-energized rail can be established as occasion may require.

Generally stated, the invention consists in the provision of an electric circuit which is established automatically between the central office and the vehicle through the third rail which was de-energized to produce an operation of said train movement regulating means conformable to danger conditions, which circuit shall be contemporaneous with, and without effect on, the said operation of said means and may be utilized as desired for the purposes of train control; the invention further consists in provision for the operation of an element of the central office apparatus responsive to the movement of the vehicle in relation to a de-energized third rail, such operating element preferably being a recording element where-

by a record of the movements of vehicles in relation to third rails which have been de-energized to produce an operation of the train movement regulating means conformable to danger conditions may be effected and maintained.

The invention further consists generally in novel features of structure and combination appertaining to the transmission of electrical currents between the central office and the vehicle through the third rails and also to the recording at the central office of the movements of the vehicle in relation to de-energized third rails.

The invention is illustrated in the accompanying drawing wherein:

Figure 1 is a schematic diagram showing the apparatus at the despatcher's office in relation to the track of the railroad.

Figure 2 is a schematic diagram of the cab circuits and equipment.

Along the track 1, which may be assumed to run east and west are a number of stations A, B, C, D, E, etc., which may be actual stations or other convenient dividing points between blocks, station A being assumed to be a terminal of the road or of a division thereof. At the eastern and western entrance of each station there is a siding 2, which in the diagram of Fig. 1 is shown disproportionately large in relation to the distance between adjacent stations or blocks. The signal rails, that is to say the short third rails or ramps, are also provided at the eastern and western entrance of each station, and, preferably and in accordance with known practice, are connected in pairs, each pair comprising a "home" rail 3 and a "distant" rail 4, these rails being conveniently located on the right hand side of the track for each direction of train movement. The car or locomotive indicated diagrammatically by the showing of the truck T is provided with a movable shoe 5 for engagement with the signal rails, the arrangement being such that the shoe 5 will first engage the distant rail and thereafter the "home" rail.

The different cab circuits are controlled by different electrical conditions of the rails 3 and 4, and in the embodiment selected for the purpose of illustration include signal lamps as the regulating devices. An energized condition of the third rails produces

a clear signal and a de-energized condition produces a danger signal. For the purpose of illustration it is assumed that the rails are to be energized by direct current.

- 5 The cab circuits and the signal lamps for regulating train movements are shown in Figure 2. A simple arrangement of two-lamp circuits, such as is shown in my prior Patent, No. 941,541 of November 30, 1909, 10 has been selected for the purpose of illustration. The car carries a relay CR which may be of any desired character and is used to control the operations of the signal lamps. The relay CR, as shown, includes an ordinary magnet 6 and a pivoted armature 7 15 which moves against a front contact 8 when the magnet is energized and against a back contact 9 when the magnet is de-energized. The magnet 6 is energized by current supplied through the third rails 3-4 or by current supplied from a suitable source, for example, a battery 10 carried by the car. When the shoe 5 is engaged with an electrified third rail 3-4 current flows by the wire 11 to the 20 magnet 6 and thence by the wires 12 and 13 to ground. When the shoe 5 is engaged with a de-energized third rail no current is supplied to the magnet 6. When the shoe 5 passes from an energized third rail current 25 is supplied to the magnet by the battery 10 and the energization of the magnet is thus continued until it is interrupted, as will presently appear, by the engagement of the shoe 5 with a de-energized third rail. When the shoe 5 passes from a de-energized third rail no current is supplied to the magnet which thus remains de-energized until such 30 time as its energization is established by the engagement of the shoe 5 with an energized third rail. When the magnet 6 is energized 35 a clear signal is displayed and when the magnet 6 is de-energized a danger signal is displayed, the clear signal being given by a green lamp 14 and the danger signal by a red lamp 15.

One pole of the battery 10 is permanently connected to the armature 7 and said battery is in a normally maintained circuit which establishes the lighting of the clear signal 40 lamp 14. Such circuit includes the magnet 6, the armature 7, the front contact 8 and the wires 11 and 12 and is completed by a suitable switch 16 movable with the shoe 5 and normally (i.e. when said shoe is not engaged with a third rail) engaging a contact 45 17 connected by a wire 18 to the front contact 8. This circuit may be traced as follows: battery 10, armature 7, front contact 8, wire 18, contact 17, switch 16, shoe 5, 50 wire 11, magnet 6, and wires 12 and 19 to battery. The circuit thus traced is broken at the contact 17 when the shoe 5 is in engagement with a third rail.

When the magnet 6 is energized another 55 circuit is established for the lamp 14 and

which may utilize the battery 10 or other suitable source. As shown the circuit for the lamp 14 may be traced from the battery 10 through armature 7, front contact 8, wire 20, lamp 14, and wires 21, 19^a and 19 to 7 battery.

When the magnet 6 is de-energized a circuit is established for the lamp 15 and which may utilize the battery 10 or other suitable source. As shown, the circuit for the lamp 15 may be traced from battery 10 through armature 7, back contact 9, wire 22, lamp 15, and wires 23, 19^a and 19 to battery.

It will be noted that the particular signal established in accordance with the condition 8 of the third rail with which the shoe 5 is engaged is continued as the vehicle passes by the third rail and until the shoe 5 engaged with a third rail having a different electrical condition. The third rail is formed, in accordance with standard practice, with inclined end portions (not shown) to facilitate the engagement of the shoe 5 and the parts are so arranged that the switch 16 will engage the contact 17 before the shoe 5 completely disengages the third rail. Consequently, in the case of an energized third rail, the energization of the magnet effected through the circuit in which said third rail is included is uninterrupted continued when the vehicle passes beyond the third rail by the local holding circuit which includes the battery 10 and the switch 16; and in this way the lighting of the lamp 14 to give a clear signal as effected by the contact of the shoe 5 with an energized third rail is continued until the shoe 5 engages a de-energized third rail, at which time, the local holding circuit being broken at the contact 17, no current is supplied to the magnet 6.

When the magnet is thus de-energized by the engagement of the shoe 5 with a de-energized third rail, the armature 7 falls against the back contact 9 and closes the circuit of the lamp 15, thus producing the danger signal which is continued until the shoe 5 engages an energized rail, it being apparent that after the vehicle leaves a de-energized rail the local holding circuit of the magnet is broken at the contact 8, and the armature 7 will remain in engagement with the contact 9 until such time as current is supplied to the magnet through an energized third rail.

The electrical condition of the third rails is subject to control by switches at the dispatcher's office and which are designated generally as 26, there being a switch for each station or block divisions which they control. In the present diagram it is assumed that each switch is connected to the third rails at the adjacent eastern and western entrances of adjacent blocks. The switches are indicated merely diagrammatically in

the drawings and are differentiated by the same letters as the stations to which they severally correspond. As shown, they include rocker shafts 27 by which they are mounted and each shaft is connected by a wire 28 to the signal rails 3-4 of the corresponding stations.

Any suitable arrangement may, of course, be provided for supplying current to the 10 third rails in connection with their control from a remote point i. e. the despatcher's office. As herein shown the third rails are energized by current supplied from a common battery 29 which is connected by a line 15 wire 30^a to a rail of the track 1 and which may be utilized as the source of current for certain electrical receiving devices at the despatcher's office. The other pole of the battery 29 is connected to the stationary contacts 20 of the switches 26, the connection including a common wire 30 and wires 31 and 32 leading to the switch contacts. The central station equipment may include station relays DR for a purpose to be described and 25 the magnets 33 of said relays are shown as connected between the wires 31 and 32.

The circuit from the battery 29 through a third rail is completed by the engagement of the shoe 5 of the car with such third rail 30 and by the closure of the corresponding switch 26, the switches AB 26, CD 26, and DE 26 being shown as closed. The despatcher can at any time de-energize the third rails at the entrance of any block in 35 order to effect a danger signal when the shoe 5 of the approaching vehicle engages such third rails. This is accomplished by disengaging the stationary and movable contacts of the battery 29 at the switch; the drawing 40 shows the switches BC 26 and EF 26 as thus opened, thereby to de-energize the third rails at the adjacent entrances of blocks B and C and E and F.

The system includes suitable apparatus at 45 the despatcher's office for making a record of train movements and one form of such apparatus is herein shown diagrammatically. As shown the recording apparatus includes a chart 39 in the form of a web 50 and which is trained over any suitable arrangement of guiding and winding rollers. The web 39 bears regularly spaced transverse or horizontal lines 40 indicative of divisions of time and longitudinal or vertical lines 41 and 41^a indicative of the stations to which they severally correspond, as shown in the drawings by the lines AB, BC, CD, DE, and EF, etc. The shaft 42 of the winding roll of said web may be clock driven 55 in any suitable manner but it is preferably driven by a ratchet wheel 43 in turn operated by a pawl 44 carried by the armature of an electro-magnet 45. Current for the operation of the magnet 45 is supplied by a battery or 60 other suitable source 46, the circuit being

traced as follows: battery 46, wires 47 and 48, clock switch 49, wire 50, magnet 45 and wires 51 and 52 to battery.

The system includes means for recording the movements of the vehicle in relation to 70 station or block divisions for which clear signals have been given and the devices for making such records are conditioned for operation by the despatcher, their co-ordination being effected by the station relays DR 75 by which the operating circuits of said devices are controlled. For the purpose of recording the movements of the vehicle in relation to station or block divisions for which clear signals have been given it is 80 preferred to employ punches 53 which form recording perforations in the chart and are arranged to operate on or adjacent the lines 41. The punches 53 are operated by magnets 54 which are energized by current from the battery 46 or other suitable source. The circuit of the magnet 54 provided for a particular station or block division is completed when a vehicle has its shoe 5 in engagement with an energized third rail at 85 the entrance of such station or block division. The drawings show such a vehicle in block C and the diagram assumes that the shoe 5 of the vehicle is engaged with the energized third rail 4 at (i. e. suitably in advance of) the entrance of block D. In such case the relay DR for station C is energized and the circuit of the corresponding magnet 54 may be traced as follows: battery 46, 90 wires 47 and 49, armature 55 and front contact 56 of relay DR, wire 57, magnet 54 and wires 58, 59 and 52 to battery 46. In all cases the circuits of magnets 54 are completed by corresponding armatures 55 in engagement with their front contacts 56 and hence for their completion it is required that the relays DR be energized. Since these relays can never be energized except as the corresponding third rails are electrified by 95 current supplied by the battery 29, it follows that under danger conditions when the third rails are de-energized no operation of the corresponding punch 53 can take place.

The invention provides for the operation of an element of the central office apparatus 100 responsive to the movement of the vehicle in relation to a de-energized third rail and also provides for an electrical circuit between the central office and the vehicle through the third rail which was de-energized to produce an operation of the train movement regulating means conformable to danger conditions, i. e. an operation of the danger signal, which circuit is contemporaneous with, and without effect on, the danger signal. The central office element which operates responsive to the movement of the vehicle in relation to a de-energized third rail is preferably a recording element, 105 (which may be conveniently designated at a

dead rail recording element) in co-operation with the chart 39; and the circuit between the central office and the vehicle is preferably used to produce the operation of such recording element.

The dead rail recording elements are provided for the several station or block divisions of the road and preferably consist of perforating punches 60 arranged to operate on or adjacent the lines 41. The punches 60 are operated by magnets 61, which are supplied with current from any suitable source, preferably the battery 46, the operating circuits of the magnets 61 being controlled in the embodiment disclosed by station relays AR and being closed through the armatures 62 and front contacts 63 of said relays when the magnets 64 thereof are energized. The circuit of the magnet 61 corresponding to station E is shown as closed and may be traced as follows: battery 46, wires 47 and 49, armature 62, front contact 63, wire 65, magnet 61 and wires 66, 59 and 52 to battery.

The current which supplies the relays AR differs markedly from the current which is normally supplied to the third rails. Where, as in the present embodiment, the current normally supplied to the third rails is direct it is preferred to use alternating current for the relays AR. The alternating current generator may be located at the central office but preferably, and as shown, is carried by the vehicle, being indicated at 67. The magnets 64 are connected by wires 68 to a rail of the track 1 and by wires 69 to contacts 70 which are engaged by auxiliary arms 71 of the switches 26 only when said switches are opened. One pole of the generator is connected to ground by a wire 72 and the other pole is connected to an armature 73 coupled to the armature 7 and, when the magnet 6 is de-energized, engaging a back contact 74 connected by a wire 75 to a contact 76 which is engaged by the switch 16 when the shoe 5 is in engagement with a third rail 3-4. The circuit of the generator 67 through any relay AR is thus controlled jointly by the switch 16 and the switch 26 corresponding to said relay. Suitable impedance coils 77 are placed in the wires 11 and 13, a condenser 78 is placed in the wire 72 and condensers 79 are placed in the wires 68, these elements preventing mutual interference between the direct and alternating current circuits.

When the shoe 5 of a vehicle engages upon a de-energized third rail the magnet 6 is de-energized and the danger signal is given by the red lamp 15 in the manner above explained and as shown in Figure 2. At the same time the circuit of the generator 67 through the relay AR corresponding to said initially de-energized rail is

completed through said rail without affecting the danger signal. In the present embodiment this is due to the impedances 77 which prevent the flow of alternating current to the magnet 6. In the diagram the circuit of the relay AR of station E is assumed to be closed and may be traced as follows: generator 67, wire 72, a rail of track 1, wire 68, magnet 64 of relay AR, wire 69 to contact 70 and auxiliary arm 71, shoe 5, switch 16, contact 76, wire 75, contact 74 and armature 73 to generator. The energization of a relay AR produces an operation of the corresponding punch 60 which thus makes a perforation in the chart 39 each time that the shoe 5 passes over a de-energized third rail.

Having described my invention, I claim:

1. In a system of train control, the combination with a vehicle and a line of track, of an element associated with the track and upon which electric current may be impressed, manually operated central office means for energizing or de-energizing said element, electrical receiving devices in the vehicle, means for severally conditioning said devices in accordance with the condition of said element as effected by said central office means, means involving the co-operation of said vehicle and said element as initially de-energized by said central office means for automatically establishing an electric circuit between said vehicle and the central office and an electrical receiving device in said circuit.

2. In a system of train control, the combination with a vehicle and a line of track, of an element associated with the track and upon which electric current may be impressed, central office means for energizing or de-energizing said element, electrical receiving devices in the vehicle, means for severally conditioning said devices in accordance with the condition of said element as effected by said first named means, means involving the co-operation of said vehicle and said element as initially de-energized by said first named means for automatically establishing an electric circuit between said vehicle and the central office and an electrical receiving device in said circuit.

3. In a system of train control, the combination with a vehicle and a line of track, of an element associated with the track and upon which electric current may be impressed, manually operated central office means for energizing or de-energizing said element, electrical receiving devices in the vehicle, means for severally conditioning said devices in accordance with the conditions of said element as effected by said central office means, recording means at the central office, and means involving the co-operation of said vehicle and said element

as initially de-energized by said central office means for producing an operation of said recording means.

4. In a system of train control, the combination with a vehicle and a line of track, of an element associated with the track and upon which electric current may be impressed, central office means for energizing or de-energizing said element, electrical receiving devices in the vehicle, means for severally conditioning said devices in accordance with the condition of said element as effected by said first named means, recording means at the central office, and means involving the co-operation of said vehicle and said element as initially de-energized by said first named means for producing an operation of said recording means.

5. In a system of train control, the combination with a vehicle and a line of track, of an element associated with the track and upon which electric current may be impressed, manually operated central office means for energizing or de-energizing said element, electrical receiving devices in the vehicle, means for severally conditioning said devices in accordance with the condition of said element as effected by said central office means, recording means at the central office and means involving the co-operation of said vehicle and said element as initially de-energized by said central office means for automatically establishing an electric circuit between said vehicle and the central office, said recording means being responsive in operation to said circuit.

6. In a system of train control, the combination with a vehicle and a line of track, of an element associated with the track and upon which electric current may be impressed, central office means for energizing or de-energizing said element, electrical receiving devices in the vehicle, means for severally conditioning said devices in accordance with the condition of said element as effected by said first named means, recording means at the central office, and means involving the co-operation of said vehicle and said element as initially de-energized by said first named means for automatically establishing an electric circuit between said vehicle and the central office, said recording means being responsive in operation to said circuit.

7. In a system of train control, the combination with a vehicle and a line of track, of an element associated with the track and upon which electric current may be impressed, manually operated central office means for energizing or de-energizing said element, electrical receiving devices in the vehicle, means for severally conditioning said devices in accordance with the condition of said element as effected by said central

office means, means at the central office for recording the energized condition of said element as effected by said central office means, means involving the co-operation of said vehicle and said element as energized by said central office means for producing the operation of said recording means, means at the central office for recording the de-energized condition of said element as effected by said central office means, and means involving the co-operation of said vehicle and said element as initially de-energized by said central office means for producing the operation of said last named recording means.

8. In a system of train control, the combination with a vehicle and a line of track, of an element associated with the track and upon which electric current may be impressed, central office means for energizing or de-energizing said element, electrical receiving devices in the vehicle, means for severally conditioning said devices in accordance with the condition of said element as effected by said first named means, means at the central office for recording the energized condition of said element as effected by said first named means, means involving the co-operation of said vehicle and said element as energized by said first named means for producing an operation of said recording means, means at the central office for recording the de-energized condition of said element as effected by said first named means and means involving the co-operation of said vehicle and said element as initially de-energized by said first named means for producing an operation of said last named recording means.

9. In a system of train control, the combination with a vehicle and a line of track, of an element associated with the track and upon which electric current may be impressed, manually operated central office means for energizing or de-energizing said element, electrically operated clear and danger signals in the vehicle, means for establishing the operation of said signals in accordance with the condition of said element as effected by said central office means, means at the central office for recording the danger signal and means involving the co-operation of said vehicle and said element as initially de-energized by said central office means for producing the operation of said recording means.

10. In a system of train control, the combination with a vehicle and a line of track, of an element associated with the track and upon which electric current may be impressed, manually operated central office means for energizing or de-energizing said element, electrically operated clear and danger signals in the vehicle, means for establishing the operation of said signals in accordance with the condition of said element as effected

6 by said central office means, means at the central office for recording the danger signal, and means involving the co-operation of said vehicle and said element as initially de-energized by said central office means for automatically establishing an electric circuit between said vehicle and the central office, the danger signal recording means being responsive in operation to said current.

10 11. In a system of train control, the combination with a vehicle and a line of track, of an element associated with the track and upon which electric current may be impressed, central office means for energizing or de-energizing said element, electrically operated clear and danger signals in the vehicle, means for establishing the operation of said signals in accordance with the condition of said element as affected by said first named means, means at the central office for recording the danger signal and means involving the co-operation of said vehicle and said element as initially de-energized by said first named means for producing the operation of said recording means.

12. In a system of train control, the combination with a vehicle and a line of track, of an element associated with the track and upon which electric current may be impressed, central office means for energizing or de-energizing said element, electrically operated clear and danger signals in the vehicle, means for establishing the operation of said signals in accordance with the condition of said element as effected by said first named means, means at the central office for recording the danger signal, and means involving the co-operation of said vehicle and said element as initially de-energized by said first named means for automatically establishing an electric circuit between said vehicle and the central office, the danger signal recording means being responsive in operation to said circuit.

14. In a system of train control, the combination with a vehicle and a line of track, of an element associated with the track and upon which electric current may be impressed, manually operated central office means for energizing or de-energizing said element, electrically operated clear and danger signals in the vehicle, means for establishing the operation of said signals in accordance with the condition of said element as effected by said central office means, means at the central office for recording the clear signal, means involving the co-operation of said vehicle and said element as energized by said central office means for producing the operation of said recording means, means at the central office for recording the danger signal and means involving the co-operation of said vehicle and said element as initially de-energized by said central office means for producing the operation of said recording means, means at the central office for recording a danger signal.

the operation of said last named recording means.

14. In a system of train control, the combination with a vehicle and a line of track, of an element associated with the track and upon which electric current may be impressed, central office means for energizing or de-energizing said element, clear and danger signals in the vehicle, means for establishing the operation of said signals in accordance with the condition of said element as effected by said first named means, means at the central office for recording a clear signal, means involving the co-operation of said vehicle and said element as energized by said first named means for producing the operation of said recording means, means at the central office for recording the danger signal, and means involving the co-operation of said vehicle and said element as initially de-energized by said first named means for producing the operation of said last named recording means.

15. In a system of train control, the combination with a vehicle and a line of track, of an element associated with the track and upon which electric current may be impressed, manually operated central office means for energizing or de-energizing said element, clear and danger signals in the vehicle, means for establishing the operation of said signals in accordance with the condition of said element as effected by said central office means, means at the central office for recording a clear signal, means involving the co-operation of said vehicle and said element as energized by said central office means for producing the operation of said recording means, means at the central office for recording a danger signal and means involving the co-operation of said vehicle and said element as initially de-energized by said central office means for automatically establishing an electric circuit between said vehicle and the central office, the danger signal recording means being responsive in operation to said circuit.

16. In a system of train control, the combination with a vehicle and a line of track, of an element associated with the track and upon which electric current may be impressed, means for energizing or de-energizing said element, clear and danger signals in the vehicle, means for establishing the operation of said signals in accordance with the condition of said element as effected by said first named means, means at the central office for recording a clear signal, means involving the co-operation of said vehicle and said element as energized by said first named means for producing the operation of said recording means, means at the central office for recording a danger signal.

nal, and means involving the co-operation of said vehicle and said element as initially de-energized by said first named means for automatically establishing an electric circuit between said vehicle and the central office, the danger signal recording means being responsive in operation to said circuit.

17. In a system of train control, the combination with a vehicle and a line of track, of an element associated with the track and upon which electric current may be impressed, a current source, a switch at the central office and by means of which a circuit supplied by said source may be established through said element, electrical receiving devices in the vehicle, means for severally conditioning said devices in accordance with the condition of said element as effected by said central office switch, a second current source and means co-operative with said switch in the position thereof in which said circuit is opened for closing a second circuit supplied by said second current source through said element.

18. In a system of train control, the combination with a vehicle and a line of track, of an element associated with the track and upon which electric current may be impressed, a current source, a switch at the central office and by means of which a circuit supplied by said source may be established through said element, electrical receiving devices in the vehicle, means for severally conditioning said devices in accordance with the condition of said element as effected by said central office switch, a second current source of different characteristic and means co-operative with said switch in the position thereof in which said circuit is opened for closing a second circuit supplied by said second current source of different characteristic through said element.

19. In a system of train control, the combination with a vehicle, a central office, a line of track, and an element associated with the track and upon which electric current may be impressed, of two circuits through

said element between the central office and the vehicle, electrical receiving devices in said circuits, and means for automatically establishing one of said circuits when the other is opened, one of said circuits requiring for its establishment the initial de-energization of said element.

20. In a system of train control, the combination with a vehicle, a central office, a line of track, and an element associated with the track and upon which electric current may be impressed, of two circuits through said element between the central office and the vehicle, sources of current of different characteristics for the respective circuits and means for automatically establishing one of said circuits when the other is opened, one of said circuits requiring for its establishment the initial de-energization of said element.

21. In a system of train control, the combination with a vehicle, a central office, a line of track, and an element associated with the track and upon which electric current may be impressed, of two circuits through said element between the central office and the vehicle, electrical receiving devices in said circuits, and means including a common manually operated central office controlling switch for automatically establishing one of said circuits when the other is opened, one of said circuits requiring for its establishment the initial de-energization of said element.

22. In a system of train control, the combination with a vehicle, a central office, a line of track, and an element associated with the track and upon which electric current may be impressed, of two circuits through said element between the central office and the vehicle, means for automatically establishing one of said circuits when the other is opened, one of said circuits requiring for its establishment the initial de-energization of said element, and recording devices at the central office severally responsive in operation to the respective circuits.

In testimony whereof I affix my signature.
PAUL J. SIMMEN.
